UNITED STATES PATENT OFFICE.

CHARLES B. CLARK, OF DETROIT, MICHIGAN.

DESIGN FOR A HINGE.

SPECIFICATION forming part of Design No. 11,871, dated July 20, 1880.

Application filed May 31, 1880. Term of patent 14 years.

To all whom it may concern:

Be it known that I, CHARLES B. CLARK, a citizen of the United States, residing at Detroit, in the county of Wayne and State of Michigan, have invented and produced a new and original Design for Hinges, (Case B,) of which the following is a specification, reference being had to the accompanying drawings, forming part thereof.

10 Figure 1 is a front view of my newly-designed blind-hinge. Fig. 2 is a section on the line $x\ x$, and Fig. 3 a section on the line $y\ y$ of Fig. 1, these three views being deemed necessary to fully illustrate my design.

15 The leading features of my design consist in an ornamental tip formed at each or either end of the hinge-pintle; but the ornamental effect of the hinge as a whole is greatly enhanced by a diamond or lozenge shaped panel 20 surrounded by a bead on the front of the hinge-eye, by a tablet-panel arranged to the right of the diamond-shaped panel and sunk into the front of the narrow portion of the hinge-eye, by the undulating or scroll-like contour which is given to the longitudinal edges 25 of the leaves and a bead which follows the entire outer edge of said leaves, and also by beads which surround the countersinks of the screw-holes.

30 The letter A designates the hinge-pintle, and B the ornamental tips at the top and bottom. C C are the leaves, having their longitudinal edges undulating or scroll-like in contour; and D indicates the bead projecting frontward and following the entire outer edges of 35 the leaves.

The screw-holes e are countersunk in the usual manner, and each is surrounded by a bead, E.

F designates the hinge-eye; G, the diamond or lozenge shaped panel surrounded by a bead, h, on the front of this eye; and I shows the tablet-panel sunk into the front of the narrow portion of the eye.

What I claim is—

1. The design for a blind-hinge herein shown and described, the same consisting in the ornamental tip B at the top of the hinge-pintle, the diamond or lozenge shaped panel G, surrounded by the bead h on the front of the hinge-eye, the tablet-panel I, sunk into the narrow portion of the eye of the hinge, and the leaves C C, having the undulating or scroll edges, followed by a bead, D.

2. The design for a blind-hinge herein shown and described, the same consisting in the ornamental tip B at the top of the hinge-pintle, the diamond or lozenge shaped panel surrounded by a bead, h, on the front of the hinge-eye, the tablet-panel I, recessed into the contour of the eye portion of the hinge, the leaves C C, having the undulating or scroll-like edges, followed by the bead D, and provided with the countersunk screw-holes e, each surrounded by a bead, E.

In testimony that I claim the foregoing I have hereunto set my hand in the presence of two witnesses.

CHARLES B. CLARK.
